(57) **CLAIM**

The ornamental design for a shield for a power sprayer wand, as shown and described.

DESCRIPTION

FIG. 1 is a top perspective view of a shield for a power sprayer wand, showing my new design;

FIG. 2 is a bottom perspective view thereof;

FIG. 3 is a front view thereof;

FIG. 4 is a back view thereof;

FIG. 5 is a top view thereof;

FIG. 6 is a bottom view thereof;

FIG. 7 is a right side thereof; and,

FIG. 8 is a left side thereof.

The dashed lines in the drawings depict portions of the design that form no part of the claim.
